Inventor,

Ikko Matsumoto,

By Joseph A. Minturn
Attorney,

UNITED STATES PATENT OFFICE.

IKKO MATSUMOTO, OF INDIANAPOLIS, INDIANA.

DESIGN FOR A RING OR SIMILAR ARTICLE.

SPECIFICATION forming part of Design No. 34,155, dated March 5, 1901.

Application filed February 4, 1901. Serial No. 46,036. Term of patent 7 years.

To all whom it may concern:

Be it known that I, IKKO MATSUMOTO, a citizen of the United States, residing at Indianapolis, in the county of Marion and State of Indiana, have invented and produced a certain new Design for a Ring or Similar Article, of which the following is a specification.

Figure 1 represents a side view of the ring, Fig. 2 an edge view, and Fig. 3 a top or plan view.

Like letters of reference indicate like parts throughout the several views of the drawings.

A represents the jewel, which is brilliant cut, and B is the body or band, which terminates on either side of said jewel in a representation of a tiger's paw with toes C expanded and claws D projecting from said toes and grasping said jewel.

E represents lumps or projections below each toe and represents the first joints of the 20 said toes. The outside toes of each paw have but one claw to each adjacent pair of toes. The outer surface of the paws is furrowed roughly and irregularly to represent hair.

Having thus fully described my invention, 25 what I claim as new, and desire to secure by Letters Patent, is—

The design for a ring or similar article as herein shown and described.

In witness whereof I have hereunto set my 30 hand and seal, at Indianapolis, Indiana, this 31st day of January, A. D. 1901.

IKKO MATSUMOTO. [L. S.]
